CALCULATOR

Alfred P. West, Richmond, Va.

Application August 29, 1939, Serial No. 292,376

11 Claims. (Cl. 235—61)

My invention relates to calculators, and particularly to a calculator designed for use in calculating allowable circuit loading, voltage regulation, for circuit scheduling purposes; and for voltage regulation improvement on power distribution circuits serving all types of loads met with in the public utility business, as, for instance, loads for residences, business offices, street lighting, playgrounds, athletic fields, tennis courts; and for advertising, decorative, and industrial purposes.

The primary object of all voltage regulation is either to supply a constant and predetermined voltage at the load, or to vary the voltage as the nature of the load may require.

Continuity of service is generally recognized as the prime requisite in the distribution of electric energy; and the quality of the service is next in importance. The value of accurate voltage control naturally varies for different applications of power, and is probably at a maximum in incandescent lighting.

Power used for illumination comprises the bulk of all power sold to-day. The illumination obtained from the incandescent lamp is affected to a greater extent by changes in voltage than is the performance of other electrical devices. The candle-power output of the lamp, in percent of rated candle-power, is the criterion by which the quality of the service is judged.

How important voltage regulation is, in the case of the Mazda lamp for instance, will be understood when it is noted that a one percent change in voltage will produce a three and one half percent change in candle-power; and that for each one per cent increase in applied voltage there is an increase of one and six tenths percent in the power consumed by the lamp.

The economy of generating electric power by the use of large generating units in generating stations of great capacities, and in distributing the power at high voltages, is generally recognized. By controlling the voltage of the individual feeders emanating from substations other economies are possible. By controlling the bus voltage of the substation, or by regulating the voltage of its individual feeders, a number of substations can be supplied by a single transmission circuit. Economies can also be effected by net-working or interconnecting power transmission circuits.

In areas in which the electric load is increasing from year to year, utilities are confronted with the problem of voltage regulation improvement. This improvement can be accomplished by the

use of voltage regulators, or by an increase in the size of the line copper. The choice between voltage regulators to compensate for the voltage drop in a feeder, and an increase in the section of the line copper to decrease the drop, depends on the relation between the cost of the regulator and of the regulator and line losses, and the cost of the additional line copper (sufficient to decrease the line drop to an allowable amount) plus the line loss.

Constant voltage can be maintained at the circuit load center by means of a regulator; but constant voltage at that point cannot be maintained by any increase in line copper.

We are concerned with certain problems in efficiently operating a power distribution system. The first problem confronting us is transformer impedance volts drop or transformer regulation, at our power distributing stations, commonly called substations. Next we are concerned about impedance volts drop (ZI) in our distribution system conductors; most of which occurs in the express feeder portion of the circuit. An express feeder is that portion of the circuit between the substation and point on the distribution circuit at which some distribution customer load is being supplied with electric service. The voltage drops in the individual distribution system transformers are of some concern to us; as is also the voltage drop in the secondary conductors serving the individual customers. With the advent of large pumping stations in strictly residential areas, and with the growth of air-conditioning load in the newly developed community theatre, the control of motor starting current to a value which will not produce perceptible voltage flicker to other customers on the circuit, and which will allow sufficient static and starting motor torque, has become of importance. Another problem that is becoming of growing importance is the application of capacitors to power distribution systems for purposes of absorbing reactive Kva.

The object of my invention is to solve these and other problems which arise in connection with the efficient operation of a power distribution system. The design of my calculator is based upon the solution of these problems by vector methods.

In the following explanation of my instrument and its uses, I make use of certain well known symbols; for instance—RI to represent resistance volts drop; XI to represent reactance volts drop; ZI to represent impedance volts drop; p.f. to represent power factor; X—X to represent the hori-

horizontal reference line through a center; Y—Y to represent the vertical reference line through the center; % to represent per cent. Also E_s for voltage at sending station; E_r voltage at receiving station; $\cos \theta$ for the substation power factor, and $\cos \beta$ for the relative power factor at the end of the express feeder.

In the drawings which accompany and form a part of this specification:

10 Figure 1 shows my instrument as it is arranged for the solution of line drop problems in express feeders;

15 Figure 2 shows the instrument arranged for the solution of transformer impedance drop problems;

Figures 3 to 8 inclusive show parts of the instrument;

20 Figure 9 shows the development of the completed part shown in Figure 4;

25 Figure 10 is a table used in the development of the part shown in Figure 4; and Figure 11 shows a vector solution of the problem set up in Figure 1.

30 In Figure 1, the numeral 1 indicates a base-board, in which is cut a straight slot 2, substantially parallel with the edge of the board 1. A semicircular protractor 3 is slidably mounted on the base-board 1, having on its back two lugs, 4, one on either side of the center of the protractor scale, and engaging in the slot 2 to guide the movement of the protractor. On 3 is drawn a circular scale 10, whose axes intersect at the center 5, and whose horizontal axis or X—X line is parallel with the center line of the slot 2 in board 1. A pivot pin 6, which is shown in detail in Figure 7, passes through the center 5 and through the slot 2. After adjustment by sliding along the slot, protractor 3 is held in place on the board by the tightening of the nut 40 7, which may be screwed up against the back of the board.

40 On this pin 6, when the instrument is completely assembled, are also pivoted the chart 9, shown in detail in Figure 4; the chart 35, shown 45 in detail in Figure 5; and the scale 40, shown in detail in Figure 6.

50 A straight-edged scale 20 is pivoted on a fixed pin 21, the center of which is set in line with the X—X line of scale 10. The pivot on scale 20 is on the zero mark. On this scale 20 I have slidably mounted another protractor 25 (see Figures 1 and 8).

55 The scale 10 is graduated in terms of power factor. This graduation is determined by converting the angle of displacement from the Y—Y line or vertical axis of the protractor into p. f. by the formula $\cos \theta = p. f.$ On the left of the Y—Y line the graduations are for lagging p. f.; and on the right of the Y—Y line they are for leading p. f. Unity p. f. is represented at the intersection of the Y—Y line with the scale 10. The intersection of the X—X line with the scale 10 represents zero p. f.

60 The chart 9, which is also pivoted on the pin 6, is shown in detail in Figure 4. On this chart the radial lines represent the directions of the ZI volts drop vectors, encountered in the solution of voltage drop problems in express feeders, for all wire sizes commonly used in commercial practice. The development of these ZI vectors is shown in Figures 9 and 10, to which I refer.

65 In commercial practice overhead conductors for 3-phase circuits are usually constructed so that their effective spacing is 22.6 inches or 53

inches. The effective conductor spacing is determined from the formula

$$D = \sqrt[3]{AB \times BC \times AC}$$

70 in which D is the effective spacing in inches; A is the A-phase conductor, B is the B-phase conductor, C is the C-phase conductor; AB is the spacing between conductors A and B, BC the spacing between conductors B and C; and AC the spacing between conductors A and C. This formula applies to conductors arranged in horizontal or in triangular spacing. From this we can develop the fact that in 22.6 inch horizontal effective spacing, the spacing AB is 14.5 inches, the spacing BC is 14.5 inches, and the spacing AC is 29 inches. Likewise, in the effective spacing of 53 inches, AB is 29 inches, BC is 59 inches, and AC is 88 inches. These two spacings are the standard spacings mostly used in the construction of 2.3 KV 3-phase circuits in the United States.

75 The directions taken by these ZI volts drop vectors in relation to the X—X and Y—Y lines are determined as follows: for the 4/0 stranded conductor (see Figure 10) $\sqrt{3} RI$ and $\sqrt{3} XI$ values in terms of volts were determined for 100,000 ampere-feet. (For 100,000 I hereinafter use 10^5 .)

80 $\sqrt{3} RI$ for 10^5 ampere-feet in a 4/0 stranded conductor = 8.92 resistance volts drop (see table in Figure 10); and the $\sqrt{3} XI$ for 10^5 ampere-feet for the same conductor is 18.98 reactance volts drop. We set off 8.92 resistance volts drop on the X—X line (Figure 9), and 18.98 reactance volts drop on the Y—Y line; and from these points on the Y—Y and X—X lines we draw rectangular coordinates. Then through the intersection of these coordinates a line is drawn to the origin, or center of the chart. This line is the ZI vector for 4/0 stranded conductor. The ZI vectors for the remaining wire sizes in Figure 9 are plotted in the same way.

85 In my instrument all scales having the same class of graduations are graduated in like units or in multiples thereof.

90 The length of the ZI vectors in Figures 4 and 9 are approximately 860 volts long; this figure being near the limit of voltage drops to be considered.

95 In the arrangement of this chart 9 (Figure 4) the ZI volts drop vectors for an effective spacing of 22.6 inches are plotted in the third quadrant; and those for an effective spacing of 53 inches are plotted in the fourth quadrant. I speak of the third quadrant or of the fourth quadrant to indicate the quadrant to the left or to the right of the Y reference line on chart 9. There is no question of positive or of negative quantities. As will be explained later in this specification, both sets of vectors are actually plotted on the left of the Y reference line.

100 In the table (Figure 10) the $\sqrt{3} RI$ and $\sqrt{3} XI$ values for 10^5 ampere-feet were calculated for the conductors enumerated on the table in Figure 10 for effective spacings of 22.6 inches and 53 inches.

105 On the chart 9, Figure 4, each vector representing a conductor size is divided into spaces; the unit space on each vector representing the ZI drop which would be created by 10^5 ampere-feet in a circuit. The lengths of these unit spaces will increase as the conductors become smaller because the drop will increase as the wire section decreases.

110 If we now connect the divisions, on the several

vectors, representing the ZI drop for a given circuit load, we develop a load-drop-line, which line will give at a glance the ZI drop for each wire size. In Figure 4 the load-drop-line $g-h$ gives at its intersection with the several vectors the phase to phase volts drop in each of the circuit wire sizes represented, for a circuit load of 20×10^5 ampere-feet. On the chart 9 the load-drop-lines are 10^5 ampere-feet apart.

10 The ZI vectors in the fourth quadrant of chart 9 are arranged for an effective spacing of 53 inches. For the sake of simplicity, and to reduce the number of parts, as will be understood later, in the fourth quadrant the wire sizes 15 are arranged in the same order as in the third quadrant. If the drawing be held in such a position that the X—X line becomes the Y—Y line, and the Y—Y line becomes the X—X line, we shall see that the load-drop-lines for the 53 inch 20 effective spacing are developed in the same manner as are the load-drop-lines for the 22.6 inch effective spacing. The old Y—Y line being short for use as the new X—X line, for convenience in reading with the protractor 25 I have extended the body of the chart 9, as at 16, and I have produced the new X—X line on this extension, as at 17.

Referring to Figure 1: the straight-edged scale 20 is pivoted at 21, this pivot being exactly in 30 line with the X—X line of protractor 3, and also in line with the graduated edge 22 of the scale, and on the zero mark. The graduations are in volts. The zero of the scale is at the pivot 21. The graduation shown in the drawing is from 35 1500 to 3000 volts, in units of 10 volts each. These volts are sending and receiving volts. For the sake of clearness in the drawings, only a small section of this graduated scale has been graduated in the smaller units, as at 23.

40 Referring again to Figure 1: 25 is a protractor, shown in detail in Figure 8. Along the lower part of this protractor there is arranged a slot 26, with loops 27 through which the straight-edged scale 20 is passed. The scale is a neat fit in the slot; 45 with just enough play between them to allow the protractor to slide on the scale. The upper edge of the slot 26, which coincides with the graduated edge of the scale 20, is taken as an X—X line of reference; and from a point about the 50 middle of its length a Y—Y line is erected at right angles to this X—X line. Taking the intersection of these two reference lines as center, the arc 30 is described. This arc is graduated in terms of power factor; these graduations being 55 developed as in the case of scale 10. The arc is drawn in the second quadrant, to read relative power factor for the problems based on an effective spacing of 22.6 inches. It will be seen that by exchanging the relative positions of the X—X 60 and Y—Y lines on chart 9 I am able to read relative power factor on the same second quadrant for problems based on an effective spacing of 53 inches. By using the chart 9 and the protractor 25 in this way, my instrument is made simpler in 65 its construction. This will be understood when we consider the problem set up on the instrument as shown in Figure 1.

For working transformer problems I use the scale 3, the protractor 20, with the chart 35 and 70 scale 40, as shown in Figure 2. Chart 35 and scale 40 are shown in detail in Figures 5 and 6 respectively. In chart 35 the X—X line is divided in ohms resistance; and the Y—Y line is divided in ohms reactance. The smallest division is one-tenth of an ohm; and the graduations

extend to three ohms. One division, or one-tenth of an ohm, is equivalent in length to thirty volts on scale 20.

Scale 40 is a straight edged scale, with the graduated edge 41 in line with the center of the 5 pivotal hole at 42. Through this hole scale 40 is pivoted to the chart 35 at the intersection of its X—X and Y—Y lines; and both are pivoted on the pin 6 with the protractor 3 and the scale 20. The graduations on the scale 40 are in volts, as in 10 scale 20; except that the volts on scale 40 are ZI volts. The zero of the scale is at the pivot, and the scale extends to 850 volts, and for convenience in units of 10 volts each.

Referring now to Figure 1: the instrument is 15 set up to solve an express feeder voltage drop problem. For the sake of example let us take the following problem: a 3-phase 4/0 express feeder, 6666.6 circuit feet long, serves a distribution load of 300 amperes per phase with a power 20 factor of .80, measured at the substation. The distribution system is a 2.3KV 3-phase delta system. The output substation voltage is 2350 volts. The effective conductor spacing is 22.6 inches. Determine the receiver voltage at the end of the 25 express feeder; and the relative p. f. at the end of the express feeder.

First, scale 20 is placed in such a position that its graduated edge passes through the center of pivot 6. Then slide protractor 3 in the slot 2 30 until its center or pivotal point is directly under the graduation representing 2350 volts on scale 20. Protractor 3 is then clamped in position. Chart 9 is then rotated until its Y—Y line is directly over .80 p. f. on protractor 3. Now multiply the current by the distance in circuit feet, and we have $300 \text{ amperes} \times 6666.6 \text{ circuit feet} = 2,000,000$ or 20×10^5 ampere-feet. Now swing the scale 20 downward until its graduated edge passes through the 4/0 wire size vector at the 20×10^5 40 division; that is at 20×10^5 ampere-feet; and read at the point of intersection, on scale 20, 1996 receiver volts. This is the voltage at the receiver end of the express feeder.

We also wish to determine the relative p. f. 45 Holding protractor 3, chart 9, and scale 20 in position, as developed above, slide the protractor 25 on the scale arm 29 until its Y—Y line coincides with the intersection of the X—X line of chart 9 and the graduated edge of scale 20. This 50 intersection is indicated by the letter c. The relative p. f. is now read on the graduated arc on the protractor 25, at the point of its intersection with the X—X line of chart 3. The reading, 55 in relative power factor is .858.

The ordinary vector solution of this problem is shown in Figure 11. In this figure the points a' , b' , and c' are the points a , b , and c in Figure 1. The point o' in Figure 11 is the pivot o in Figure 1. In Figure 11 the angle β is the angle representing .858 power factor on the protractor 25 in Figure 1.

The vector diagram is constructed as follows:—the line $o'-a'$ is laid down to represent the substation voltage. $o'-I$ is drawn at an angle to the line $o'-a'$, the said angle being the angle whose cosine is represented by the p. f. at the substation. Through a' draw the line X—X parallel to $o'-I$; then draw Y—Y through point 70 a' perpendicular to X—X and $o'-I$ produced. From tables we determine that the R (resistance) per 1000 feet of 4/0 copper conductor is 0.0515 ohms; and the X (reactance) per 1000 feet of 4/0 copper conductor is 0.1097 ohms. In the 75

problem stated I equals 300 amperes; and the circuit length is 6666.6 feet. We have:

$$5 \quad \sqrt{3} RI = \sqrt{3} \times .0515 \times 6666.6 / 1000 \times 300 \\ = 178.2 \text{ volts drop.}$$

We also have:

$$10 \quad \sqrt{3} XI = \sqrt{3} \times .1097 \times 6666.6 / 1000 \times 300 \\ = 380 \text{ volts drop.}$$

- 15 On Figure 11: from a' lay off on the $Y-Y$ line 380 volts of XI drop. Then at the end of the XI vector on $Y-Y$, at 380 volts, draw a perpendicular to the left of $Y-Y$. Lay off on this vector line 178.2 volts of RI drop. Call the end of this vector b' . Connect b' and a' by a line. This line $b'-a'$ is the ZI volts drop, which equals $\sqrt{RI^2+XI^2}$. To complete the arithmetical equation; ZI volts drop = $\sqrt{178.2^2+380^2} = 400$ volts.
- 20 Connect o' to b' . The length of this line $o'-b'$ represents the receiver voltage, or 1996 volts.

- 25 Now we wish to determine the relative p. f. Note that the substation p. f. is equal to the cosine of θ , which is the angle between $o'-I$ and $o'-a'$. Note also that the relative p. f. at the end of the express feeder is equal to the cosine of β , which is the angle between $o'-I$ and $o'-b'$. Produce line $o'-b'$ until it intersects $X-X$ in c' . Then, because line $o'-I$ is parallel to the line $X-X$, the angle $Io'-b'$ equals the angle between $X-X$ and $o'-c'$. This is the angle which, measured by the protractor 25 in Figure 1, is .858 power factor.
- 30 Referring now to Figure 2: the protractor 3 as before is slideable on the base 1, being guided by the lugs 4 on its back engaging in the slot 2. The chart 35 is pivoted by its center to the center of the protractor 3. On the same pivot, scale 40 is pivoted. Chart 35 and scale 40, have already been described in detail.

- 35 The problem set up in Figure 2 is as follows: a 25 Kv-a 2400/120-240 volt distribution transformer, whose equivalent secondary resistance is .0329 ohm, and whose equivalent secondary reactance is .0256 ohm, is serving a load of 75 Kv-a at a relative transformer p. f. of .95. The no-load voltage on the transformer secondary side is 237.0. Our problem is to determine the voltage drop in the transformer in per cent of its secondary no-load terminal voltage. We proceed as follows:
- 40 We determine the full load secondary output current at the transformer. This equals 25000 volt-amperes divided by 240 volts; or 104.1 amperes.

- 45 To determine the equivalent secondary Z of the transformer: Z equals $\sqrt{R^2+X^2}$, equals $\sqrt{.0329^2+.0256^2}$, equals .0416 ohm.
- 50 The ZI at the above load is

$$.0416 \times 75 / 25 \times 104.1;$$

55 or 13.02 volts.

- 60 Referring to the instrument in Figure 2: bring scale 20 to its horizontal position, its graduated edge cutting the center of the pivot of protractor 3; slide protractor 3 until its center rests on 237 volts on scale 20. (In the drawings, Figure 2, the center of protractor 3 actually rests on 2370 on scale 20; that is, on 237×10 .) Rotate chart 35 until its $Y-Y$ line is on .95 p. f. on protractor 3. Now rotate the ZI volts vector scale 40 until its edge passes through a point, the coordinates of which are determined by laying off on the R and X lines on chart 35, respectively, multi-

ples of the equivalent secondary resistance and of the equivalent secondary reactance found above; namely .0329 ohm and .0256 ohm; and by drawing perpendiculars to the R and X lines through these points. This determines the direction of the ZI volts vector relative to the secondary no-load terminal voltage.

5 Now read 13.02 volts, or the ZI volts drop in the transformer, on scale 40. Bring scale 20 up until its edge coincides with 13.02 volts on scale 10 40, and read on scale 20, at the intersection, 224.4 volts. This is the secondary terminal voltage when supplying 75 Kv-a of load.

The arithmetical voltage drop in the transformer is $237 - 224.4 = 12.6$ volts; and 15

$$12.6 / 237 \times 100 = 5.31\%$$

voltage drop in the transformer.

I have described my instrument and its operation as shown in Figure 2 for solving distribution transformer problems. The instrument can be used in exactly the same way for solving substation transformer problems.

20 In the table shown in Figure 10, the seven columns taken in order give the following: (1) Wire sizes used in commercial practice; (2) Resistance in ohms for 1000 feet for each size of conductor; (3) Reactance per 1000 ft. for each size for an effective spacing of 22.6 inches; (4) the same for an effective spacing of 53 inches; (5) the $\sqrt{3} \times RI$ for 10^5 ampere-feet for each wire size; (6) the $\sqrt{3} \times XI$ for 10^5 ampere-ft. for each size of conductor for 22.6 inch effective spacing; and (7) the $\sqrt{3} \times XI$ for 10^5 ampere-feet for each size of conductor for 53 inches effective spacing.

25 Either the voltage scale 20 or the protractor 3 may be made adjustable towards the other to adjust the distance between the zero of the scale and the center of the protractor. 40

30 Note that the chart 35 shown on Figure 2 may be drawn on the same chart 9 shown on Figure 1. Their being on separate pieces of the instrument is only a matter of convenience, and for ease in reading. I prefer to make my parts of 45 transparent material.

I claim:

1. In an instrument of the class described: a voltage scale pivoted at its zero; a protractor on which are constructed $X-X$ and $Y-Y$ reference lines, set with its $X-X$ line in line with the pivot of the said voltage scale, the said protractor having also constructed upon it a circular arc whose center coincides with the intersection of the said $X-X$ and $Y-Y$ reference lines, and which arc is graduated in terms of power factor; and a chart on which are constructed $X-X$ and $Y-Y$ lines and which is pivoted at the intersection of its $X-X$ and $Y-Y$ lines to the center of the protractor, the said chart having plotted upon it 55 impedance volts drop vectors for wire sizes for a selected effective spacing.

2. In an instrument of the class described: a voltage scale pivoted at its zero; a protractor on which are constructed $X-X$ and $Y-Y$ reference 65 lines, set with its $X-X$ line in line with the pivot of the said voltage scale, the said protractor having also constructed upon it a circular arc whose center coincides with the intersection of the said $X-X$ and $Y-Y$ reference lines, and which arc is 70 graduated in terms of power factor; means for adjusting the length of the line between the zero point of the voltage scale and the center of the protractor; and a chart on which are constructed $X-X$ and $Y-Y$ reference lines and 75

which is pivoted at the intersection of its reference lines to the center of the protractor, the said chart having plotted upon it impedance volts drop vectors for wire sizes for a selected effective spacing.

5. In an instrument of the class described: a voltage scale pivoted at its zero; a protractor on which are constructed X—X and Y—Y reference lines, set with its X—X line in line with the pivot of the voltage scale, the said protractor having also constructed upon it a circular arc whose center coincides with the intersection of the said X—X and Y—Y reference lines, and which arc is graduated in terms of power factor; means for 10 adjusting the distance between the zero point of the voltage scale and the center of the protractor; and a chart on which are constructed X—X and Y—Y reference lines and which is pivoted at the intersection of its reference lines to the center of the protractor, the said chart having plotted upon it impedance volts drop vectors for several wire sizes and for a selected effective spacing, and plotted upon the vectors a series 15 of load-drop-lines giving at their intersections with the vectors the phase to phase volts drop in each of the circuit wires represented by the several vectors.

4. In an instrument of the class described: a voltage scale pivoted at its zero; a protractor on which are constructed X—X and Y—Y reference lines, set with its X—X line in line with the pivot of the said voltage scale, the said protractor having also constructed upon it a circular arc whose center coincides with the intersection of the said X—X and Y—Y reference lines, and which arc is graduated in terms of lagging power factor and in terms of leading power factor; means for 20 adjusting the distance between the zero point of the voltage scale and the center of the protractor; and a chart on which are constructed X—X and Y—Y lines and which is pivoted at the intersection of its reference lines to the center of the protractor, the said chart having plotted upon it impedance volts drop vectors for several wire 25 sizes and for a selected effective spacing.

5. In an instrument of the class described: a voltage scale pivoted at its zero; a protractor on which are constructed X—X and Y—Y reference lines, set with its X—X line in line with the pivot of the voltage scale, the said protractor having also constructed upon it a circular arc whose center coincides with the intersection of the said X—X and Y—Y reference lines, and which arc is graduated in terms of power factor lagging and 30 leading; means for adjusting the distance between the zero point of the voltage scale and the center of the protractor; and a chart on which are constructed X—X and Y—Y reference lines and which is pivoted at the intersection of its reference lines to the center of the protractor, the said chart having plotted upon it impedance 35 volts drop vectors for wire sizes for selected effective spacings; and a second protractor graduated in terms of power factor and arranged with its X—X line movable along the edge of the voltage scale so that its power factor scale may 40 be associated with the said chart to read relative power factor.

6. In an instrument of the class described: a voltage scale pivoted at its zero; a protractor on which are constructed X—X and Y—Y reference lines, set with its X—X line in line with the pivot of the voltage scale, the said protractor having also constructed upon it a circular arc whose center coincides with the intersection of the said X—X and Y—Y reference lines, and which arc is 45

graduated in terms of power factor; a chart on which are constructed X—X and Y—Y lines and which is pivoted at the intersection of its X—X and Y—Y lines to the center of the protractor, the said chart having plotted upon it impedance 50 volts drop vectors for wire sizes for a selected effective spacing; and a second protractor slidably mounted on the voltage scale, the said second protractor being graduated in terms of power factor arranged to indicate relative power factor 55 when associated with the X—X line of the said chart.

7. In an instrument of the class described: a voltage scale pivoted at its zero; a protractor on which are constructed X—X and Y—Y reference lines, set with its X—X line in line with the zero of the voltage scale, the said protractor having also constructed upon it a circular arc whose center coincides with the intersection of the said X—X and Y—Y reference lines, and which arc is 60 graduated in terms of power factor; means for adjusting the voltage scale with reference to the center of the protractor; a chart on which are constructed X—X and Y—Y lines, and which is pivoted at the intersection of its X—X and Y—Y lines to the center of the protractor, the said chart having plotted upon it an impedance volts drop vector for a wire size; and a second protractor slidably mounted on the voltage scale with its X—X line coincident with the graduated edge of the voltage scale, the said second protractor being graduated in terms of power factor to read 65 relative power factor in association with the X—X line of the said chart.

3. In an instrument of the class described: a voltage scale pivoted at its zero; a protractor on which are constructed X—X and Y—Y lines, set with its X—X line in line with the zero of the voltage scale, the said protractor having also constructed upon it a circular arc whose center coincides with the intersection of the said X—X and Y—Y reference lines, and which arc is graduated in terms of power factor lagging and leading; means for adjusting the distance between the zero point of the voltage scale and the center of the protractor; a chart on which are constructed an X—X line and a Y—Y line and which is pivoted at the intersection of its X—X and Y—Y lines to the center of the protractor, the said chart having plotted upon its impedance 70 volts drop vectors for wire sizes for selected effective spacings; and a second protractor graduated in terms of power factor and arranged with its X—X line movable along the edge of the voltage scale so that its power factor scale may 75 be associated with the said chart to read relative power factor.

9. In an instrument for determining the receiver voltage and the relative power factor at the end of an express feeder; a voltage scale pivoted at its zero point; a protractor having constructed upon it an X—X line and a Y—Y line, the X—X line being in line with the zero of the voltage scale, the said protractor having also constructed upon it a circular arc whose center coincides with the intersection of the said X—X and Y—Y lines, and which arc is graduated in terms of power factor leading on the right of its Y—Y line and in terms of power factor lagging on the left of its Y—Y line; means for moving the protractor to bring its center to the graduation on the voltage scale representing the output substation voltage; a chart having X—X and Y—Y lines pivoted at its center to the center of the protractor and rotatable on its pivot to bring 75

its Y—Y line to the substation power factor on the protractor scale, the said chart having plotted upon it ZI vectors for selected wire sizes and on the vectors voltage drop for various loads; 5 and a second protractor graduated in power factor with its X—X line coincident with and slideable along the voltage scale; so arranged with each other that when the center of the first protractor is brought to the graduation on the voltage scale representing the substation voltage, the 10 chart is rotated to bring its Y—Y line to intersect the protractor scale at the figure representing the substation power factor, and the voltage scale is rotated on its pivot to bring its scale into 15 intersection with the ZI vector on the chart at the point representing the voltage drop due to load the said vector will then intersect the voltage scale at the receiver voltage at the end of the express feeder, and also so that when the center 20 of the second protractor is brought into coincidence with the intersection of the voltage scale and the X—X line of the chart the X—X line of the chart will indicate on the scale of the second protractor the relative power factor at the 25 end of the express feeder.

10. In an instrument of the class described: a voltage scale pivoted at its zero point; a protractor having X—X and Y—Y lines and having its X—X line in line with the zero of the voltage 30 scale, the said protractor having also constructed upon it a circular arc whose center coincides with the intersection of the said X—X and Y—Y lines, and which arc is graduated in terms of power factor; means for adjusting the distance between the zero point of the voltage scale and the 35 center of the protractor; a chart having X—X and Y—Y lines and which is pivoted at its center to the center of the protractor, the said chart

being divided on its X—X line in terms of ohms resistance and on its Y—Y line in terms of ohms reactance and having upon its surface intersecting lines erected on the said divisions; and a second voltage scale pivoted at its zero point to 5 the center of the chart and graduated to read ZI volts drop at the intersections of the lines erected on the X—X and Y—Y lines, and so arranged with respect to the first voltage scale that if the first voltage scale be now rotated on 10 its pivot to bring it into intersection with the second voltage scale at the ZI volts drop reading, the scale indication on the first voltage scale at its intersection with the second voltage scale will be the secondary terminal voltage, when used for 15 solving transformer problems.

11. In a calculator for solving electrical power distribution problems: means for combining vectors of proper length and direction to obtain the desired result comprising a sending and receiving voltage scale; a protractor having constructed upon it X—X and Y—Y lines, and also having constructed upon it a circular arc whose center coincides with the intersection of the said X—X and Y—Y lines, and which arc is graduated 25 in terms of power factor and which protractor is associated with the voltage scale to indicate sending voltage; a vector chart representing impedance volts drop for wire sizes for selected spacings and divided for voltage drop at given 30 loads, and arranged to indicate receiver voltage on the voltage scale; and a second protractor graduated in terms of power factor and associated with the chart and with the voltage scale to read relative power factor at the receiving 35 voltage.
